DESIGN FOR A BUTTON

Benjamin F. Conner, Wethersfield, Conn., assignor to Colt's Patent Fire Arms Manufacturing Co., Hartford, Conn., a corporation of Connecticut

Application January 3, 1934, Serial No. 50,287

Term of patent 7 years

To all whom it may concern:

Be it known that I, BENJAMIN F. CONNER, a citizen of the United States, residing in Wethersfield, in the county of Hartford and State of Connecticut, have invented a new, original, and ornamental Design for a Button, of which the following is a specification, reference being had to the accompanying drawing.

On the drawing:

Fig. 1 is a front view of a button showing my new design.

Fig. 2 is a side view.

I claim:

The ornamental design for a button, as shown.

BENJAMIN F. CONNER.
